DESIGN FOR A PUSHCART

Charles M. Mendelson and John P. McCarthy,
Downey, Calif.

Application March 2, 1945, Serial No. 118,233

Term of patent 3½ years

(Cl. D14—14)

To all whom it may concern:

Be it known that we, Charles M. Mendelson and John P. McCarthy, citizens of the United States, residing at Downey, in the county of Los Angeles and State of California, have invented a new, original, and ornamental Design for a Push Cart, of which the following is a specification, reference being had to the accompanying drawing, forming part thereof:

Fig. 1 is a perspective view of a push cart, showing our new design;

Fig. 2 is a top plan view;

Fig. 3 is a rear end elevational view; and
Fig. 4 is a bottom plan view.

The handle member has been broken away in
Figs. 2, 3 and 4, for convenience of illustration.

We claim:

The ornamental design for a push cart, as
shown.

CHARLES M. MENDELSON.
JOHN P. McCARTHY.
